UNITED STATES PATENT OFFICE.

CHARLES A. OLcott, OF NEW YORK, N. Y., ASSIGNOR TO S. S. HEPWORTH COMPANY, OF NEW YORK, N. Y., A CORPORATION OF NEW YORK.

CENTRIFUGAL MACHINE.

Application filed June 3, 1925. Serial No. 34,641.

My invention relates to centrifugal machines, and particularly to a centrifugal basket; the object of my invention being to provide an improved construction of the basket bottom.

In the accompanying drawings—

Fig. 1 is a broken side elevation of a centrifugal basket to which my invention is applied in one form;

10 Fig. 2 is a broken inverted plan thereof;

Fig. 3 is a partial section on the line 3—3, Fig. 2; and

Fig. 4 is a partial section through a modified bottom construction.

15 In high speed centrifugals of the type to which my invention relates, such for instance as sugar centrifugals, it is customary to provide a basket bottom 15 in the form of a casting. The outer portion of this casting 20 which surrounds the central discharge opening 16, affords a plate-like bottom for the basket which is reinforced on its lower surface by short radial ribs. Inasmuch as these 25 ribs form vanes which to a certain extent, impede the drive of the centrifugal, it has been customary to house the ribs by a bottom sheet metal plate commonly referred to as a 30 "wind plate", which extends from the annulus 17 which forms the outer boundary of the discharge opening to a point considerably 35 inward of the periphery of the bottom plate 15. In order to keep the lower peripheral face of the plate 15 free from objectionable pockets in which particles may gather 40 and cause an unbalanced condition of the basket, it has been customary also to make the periphery of the plate 15 with a bead so small that it cannot accommodate the rivets. Consequently the wall 18 of the basket has 45 been secured to the bottom plate 15 by dowel pins passing through the lower margin of the basket wall 18 and entering recesses in the marginal bead of the plate 15 substantially 50 in the plane of the latter. The connection is rendered as secure as possible by shrinking on a steel ring which surrounds the dowel pins and prevents their escape. The wall of the basket is, however, rather thin, and the depth of the dowel holes in the 55 bead at the periphery of the bottom plate must be accurately regulated and the length of the dowel pins similarly determined with accuracy in order to make this attachment secure. Variations in these dimensions are 60 the source of frequent weakness and failure,

and more or less trouble with this fastening is constantly experienced. My invention provides not only a stronger bottom plate, but a more secure and readily accomplished attachment of the basket wall to the bottom 60 plate.

According to my invention the plate 15 is provided with a peripheral flange 19 of sufficient depth to receive rivets 20 by which the lower margin of the basket wall 18 is 65 connected to the flange 19. The bottom plate reinforcing ribs 21 are carried from the annulus 17 to the flange 19, and thus strengthen the plate 15 throughout its entire 70 width.

To cover the flanges, the wind plate 22 is carried from the lower margin of the annulus 17 to the basket wall 18 and is provided with an offset margin 23, which overlaps the outer face of the wall. It is preferably 75 secured in position by holding screws 24 which take into tapped holes in line with certain of the ribs 21 which are appropriately thickened at 25 adjacent the flange 19. When thus assembled, the steel band 26 is shrunk on, thus reinforcing the structure 80 at this point.

The annulus 17 may be machined at its lower margin to afford a seat 27 for the inner margin of the wind plate 22. The 85 wind plate is thus substantially flush with the lower margin of the annulus 17 and affords a smooth surface from the lower margin of the central discharge port to the periphery of the basket. It not only houses 90 in the ribs, but completely eliminates peripheral pockets in the lower face of the basket bottom in which material might tend to gather with resulting unbalance of the basket.

95 In Fig. 4 I have shown a further modification in which the bottom riveting flange 19 and ribs 21 are retained, while the wind plate and ring 26 are combined in an integral relatively heavy plate 28, which may be 100 shrunk on the basket bottom as a unit. I prefer, however, the construction shown in Figs. 1, 2 and 3 since all necessary strength is obtained in that construction without materially increasing the weight of the structure as a whole.

105 The details of my construction may be readily modified without departing from the scope of what I claim as my invention.

110 I claim as my invention.—

1. In a centrifugal basket, a bottom casting having a peripheral flange, a basket wall riveted to said flange, ribs on the lower face of said bottom casting, and a wind plate covering said ribs and overlapping said flange, together with a shrunk-on ring embracing said flange, basket wall and overlapping margin of the wind plate to reinforce the structure.
- 10 2. In a centrifugal basket, a bottom casting apertured to afford a central discharge opening, an annulus forming the outer boundary of said opening, a flange at the

periphery of the bottom casting, ribs extending between said annulus and peripheral flange, a basket wall riveted to the peripheral flange, together with a wind plate overlapping said peripheral flange and extending therefrom to the annulus to cover the ribs and afford an uninterrupted smooth surface between the flange and annulus, and means for securing the overlapped margin of said wind plate at the peripheral flange.

In testimony whereof I have signed my name to this specification.

CHARLES A. OLCOTT.
